US00D798310S

(12) **United States Design Patent** (10) Patent No.: **US D798,310 S**
(45) Date of Patent: ** *Sep. 26, 2017

(54) **DISPLAY SCREEN WITH GRAPHICAL USER INTERFACE**

(71) Applicant: **Lennox Industries Inc.**, Richardson, TX (US)

(72) Inventors: **Kyle Golden**, Plano, TX (US); **Daniel Castillo**, Richardson, TX (US); **Keith Mowery**, Richardson, TX (US); **Jayprakash Charavda**, Irving, TX (US); **Melissa Amoros**, Richardson, TX (US); **Sunil K. Khiani**, Plano, TX (US); **Steve Lazar**, San Antonio, TX (US)

(73) Assignee: **Lennox Industries Inc.**, Richardson, TX (US)

(*) Notice: This patent is subject to a terminal disclaimer.

(**) Term: **15 Years**

(21) Appl. No.: **29/535,235**

(22) Filed: **Aug. 5, 2015**

CLAIM

The ornamental design for a display screen with graphical user interface, as shown and described.

DESCRIPTION

FIG. 1 is a front view of a display screen with graphical user interface in accordance with our new design;

FIG. 2 is a front view of a second embodiment thereof;

FIG. 3 is a front view of a third embodiment thereof;

FIG. 4 is a front view of a fourth embodiment thereof; and,

FIG. 5 is a front view of a fifth embodiment thereof. The outermost broken line rectangle illustrates a display screen and forms no part of the claimed design. The remaining broken lines illustrate portions of the graphical user interface that form no part of the claimed design.
